CRAYON TRAY

Kinza B. de Launay, Charlottesville, Va.

Application December 11, 1956, Serial No. 44,156

Term of patent 14 years

(Cl. D74—1)

Fig. 1.

Fig. 2.

Figure 1 is a top plan view of a crayon tray embodying my new design;

Figure 2 is a front elevation thereof;

Figure 3 is a side elevation thereof, as seen from the left hand side of Figure 1, the opposite side being the same; and,

Figure 4 is a section view taken along the line 4—4 of Figure 2.

I claim:

The ornamental design for a crayon tray, as shown and described.
